APPARATUS FOR TRANSPORTING INGOTS

James L. Adams, Jr., Youngstown, Ohio

Application January 17, 1933, Serial No. 652,142

21 Claims. (Cl. 80—43)

The present invention relates broadly to the art of handling materials preparatory to rolling, and more particularly to the transport of either circular or straight metal ingots from the ingot 5 soaking-pit, or equivalent temperature-equalizing furnace, to a rolling mill, such, for example, as that shown and described in my co-pending application, Serial #674,661, filed June 7th, 1933, although it might conceivably be utilized with 10 other types of mill also, if desired.

One of the objects of the present invention is to assist in cutting the cost of long plates, by lowering the time and expense of handling the metal ingots or slabs used in the rolling, and incidentally increasing the possible output tonnage from 15 a single mill.

Another object is to make the handling of the metal between the heat equalizing device and the mill, or other recipient of the material, as nearly 20 automatic as possible, and so conserve operative man power at the control pulpits.

An important object is to make the ingot-feed to the mill as thoroughly interlocked as possible, to avoid chance of errors of judgment arising, 25 as in the case of a full manual control, where the operator has a number of machines on his mind, all functioning together or in substantial rotation, so that chances of confusion are accentuated by the many controls involved; or more 30 operators must be brought in to reduce the number of controls each has to handle, but thereby increasing mill costs once more.

A further object is to provide an ingot buggy or carriage which can be used with my rolling mill, either when it is operating with ring ingots, or 35 those of the customary straight type, or both in close succession.

Other objects of importance will be evident to anyone skilled in the art to which my invention 40 appertains.

With all the above and other objects in mind, I have provided a means for quickly transporting heated ring or straight ingots from furnace to mill and delivering such ingots at the latter, ready 45 for rolling, in the briefest possible time, and with the chances of error in the handling reduced to the ultimate minimum.

In the drawings, Figure 1 shows a side elevation of a preferred form of my invention, while Figure 2 shows the same in rear elevation, and Figure 3 is a plan view of the apparatus concerned.

Figure 4 illustrates a typical mill floor plan, showing one possible layout for the furnace and rolling mill equipment, with the inter-connecting

ingot-buggy railway upon which my present invention operates.

Figure 5 shows a typical form of wiring diagram for my automatic ingot-buggy, although of course the latter may be operated by hand if so preferred, without deviating from the spirit or letter of my invention. Figures 6 to 9 show track details.

In all the figures, identical parts are designated by the same part numbers.

These drawings are shown for the purpose of illustration only, and not as determining the limits of my invention, or of its possible applications, and illustrate a type of apparatus which may conveniently be utilized in connection with an ingot 15 "soaking-pit", or with an ingot heat-equalizing furnace, such, for example, as that shown and described in my co-pending application, Serial No. 655,185, filed February 4th, 1933, which refers specifically to ring-ingots, but which might 20 conceivably be so modified as to take the customary straight ingots, as well, and thus avoid the duplication of expensive mill equipment.

In accordance with the present invention, and referring now more particularly to Figure 1, 25 there may be provided an apparatus including a moving carriage 1, mounted on the flanged wheels 2, and running on track 3, said wheels 2 being driven through the usual reduction gearing 4, by the motor 5, preferably equipped with a suitable 30 electro-magnetic automatic brake 6, the motor current supply being thru the third rail 7, and spring or weight operated sliding shoe 8, flexibly mounted upon projecting arm 9, carried by suitable insulation 9a. A brake-pad is shown at 10.

Carriage 1 is provided at 11 with convenient means for rotatably supporting a ring-ingot 12 in transit, the rotational drive being indicated at 13, properly meshed with a gear 14 on the forward main driving axle of the ingot-buggy. 40 An arm for finally lifting the ring-ingot into position in line with the lower roll of the mill is indicated at 15, arranged for operation through the connecting rod 16, by the one-half revolution crank-arm 17, mounted upon gear-shaft or offset 45 crank-shaft 18, in turn driven by the worm-wheel 19, or equivalent device, functioned by motor 20 through appropriate worm or pinion 21. Arm 15 is carried upon the heavy pin 22.

The part-revolution control of crank-arm 17 50 will be given in connection with a later figure. Suitable means for retaining the ring-ingot in position axially during its transport is indicated at 23, carrying the small roller 24.

The top face of my ingot-buggy is made up of 55

the live-roll table **25**, consisting of a multiplicity of rolls, intergeared by the intermediates **26**.

Due to space limitations on the figure, the motor drive, reduction gearing, and part of the 5 inter-mediates of this live-roll system are not shown, but consist of well known elements anyway, except possibly as to the connections used, which will be indicated in a subsequent figure, 10 which will also show the means used to slow down the ingot-buggy as it approaches either of the two ends of its travel.

A ring-ingot 12a in proper raised position is shown aligned with mill-roll 27, and a straight ingot, or a slab heated ready for rolling, is indicated at 28, while at 29 I have shown the vertical position of the spur-track which runs to the outer or entering-end of the overhung mill-live-roll table 30, for delivery of flat-slabs or ingots thereon, ready for rolling in the mill 31, which has the customary non-overhung type of live-roll table 32 on its out-going side, 30, 31 and 32 being normally of the reversing form if the mill happens to be of the two-high type, as shown.

A positive limit-stop is indicated at 33, for safety, although my ingot-buggy will ordinarily have been brought to a stop just ahead of this point by the extra wheels 2a, the track 3a, brake-pad 16, and the automatic means all to be referred to later. It will of course be understood that a ring and a straight ingot will not normally be both present at the same trip of carriage.

In addition to the apparatus shown in Figure 1, my ingot-buggy will also contain various switching and contactor elements appropriate to its automatic operation, and/or, hand-operation if desired, but these will be better shown in connection with the wiring-diagram to follow in a later figure. One mill-sho is shown at 34.

40 Referring now to Figure 2, which is a view looking toward the mill from the right side of Figure 1, no new parts are brought into prominence, and no further points introduced which require explanation here, except the lifting-ears 129, the extra wheels 2a, and track 3a.

45 In Figure 3, likewise, no new parts appear, to require explanation.

In Figure 4, the rolling mill 31, with its overhung type of entering live-rolls 30, plain exit live-roll table 32, pinion-box 35, gear reduction unit 36, and variable-speed reversing motor drive 37, together with the appropriate ingot-buggy tracks 3 and 29 for the transport of circular, and of flat ingots, respectively, are shown.

55 The selection of the appropriate track will be by well known switching means, normally operated by hand, so it need not be referred to further here.

One form of furnace for heating circular ingots, or equalizing the heat therein, is indicated at 38, with selective pushers at 39, and storage space at 40, while at 41 I have shown a preferred form of my centrifugal casting unit, adapted to the rapid production of dense centrifugally-cast ring-ingots of "jarred" metal, having great uniformity of chemical and physical structure throughout, as covered more in detail in my co-pending application thereon, Serial No. 680,570, filed July 15, 1933, and my ingot application Serial #649,181, filed on December 28, 1932.

70 It is believed that the various successive stations around this centrifugal casting unit need not be gone into in detail here, or its general type of construction elaborated upon, in view of the ready reference which can be made to the appropriate application covering this subject.

In the upper right hand section of Figure 4, I have indicated an appropriate layout for casting flat or straight ingots, or slabs, in the customary vertical moulds 42, carried on the ingot-train 43, here shown over the "jarring" station 44, along which moves step-by-step the hot-metal bottom-pouring ladle 45, and which train, after a sufficient pause to permit ingot sub-surface solidification and substantial elimination of gases and non-metallics, is moved on by appropriate well-known means to the stripper station 46, and then to the "soaking pit" position 47, where the ingots are transferred to the pits by the customary "pit-cranes", (not shown, as being of usual construction). After proper equalization of the heat, and bringing to correct final temperature for rolling, the successive straight ingots are deposited by these same "pit-cranes" on the top roll-table 25 of my ingot-buggy 1, at a point near the "soaking-pit" end of railway 29, which is here equipped with appropriate speed-reducing means and limit-stops for my ingot-buggy, the functions of which will be brought out more clearly in connection with the next figures.

The hot-metal tracks are carried well beyond the soaking-pits to provide the necessary storage trackage 48 for mould servicing and re-habilitation, as well as for temporary ingot storage. The layout had to be considerably fore-shortened in the two locations 49 and 50, as indicated by the break lines here, in order to get within the limit lines of the sheet. This layout is subject to modification, however.

Referring now to Figure 5, we note, in addition to parts already covered in previous figures, the driving motor 51, and its reduction gearing 52, and series magnetic brake coil 53, for functioning the top live-roll table 25 of my ingot-buggy, and all connected in parallel with the driving motor 75, of the mill entering-end live roll table 30, thru the small side trolley-wheel 54, with retaining spring 55, and arm 56, all mounted on the insulating base 57 at rear end of ingot-buggy, and contacting with the very short section of trolley wire 58, appropriately mounted near the approach to said live-roll table 30 only, at proper height and to one side of the track 29, so that when ingot-buggy is located here close up to this table, its top live rolls will be functioned as soon as operator in pulpit starts up the rolls 30, thus delivering a new ingot or flat-slab from table 25 to the latter mill feed rolls.

The connection from trolley wire to mill roll motor is shown at 59, the opposite sides of motors being shown as grounded, for the sake of simplicity in the diagram, although such return lines will, of course, normally be insulated. 55

The two short sections of similar trolley wire 60 and 61 are, however, located so as to make contact with the similar trolley-wheels 62 and 63 only when my ingot-buggy is run in on track 3 under the live-roll table 30 and in position for delivery of a circular ingot 12 over the lower roll 27 of mill; while the short trolley-wire 64 is mounted so as to contact with its appropriate trolley-arm 65 only when the ingot-buggy is out at the extreme furnace or soaking-pit end of tracks 3 or 29, or both, as the case may be. It will be noted that the short trolley-wires 60 and 61 connect to limit-switches 66 and 67 which close when the main mill-roll 27 is in its outermost or "removed" position, and its innermost or "running" position, respectively, and that wire 60 likewise connects directly with the furnace-end trolley-wire 64, through the "starting push- 75

button" 68, located in soaking-pit control operator's pulpit or near the furnace 38, as desired.

Trolley-arm 65 has an integral-extension contact 69, which is normally closed to ground as shown, except when the ingot-buggy is at furnace-end of line, with arm 65 depressed by the short wire 64 to the dotted position indicated.

All these trolley-arms are equipped with appropriate spring returns 55, and suitable stops, (not shown), to limit the travel to about that shown in each case.

Trolley-arm and wheel 62 connects through one shunt coil 77a of single-pole contactor 70 and lead 108 to brush 71 which bears on the substantially 180 degree contact timing-segment 72, located upon the part-revolution gear 73, but insulated therefrom. Trolley 63 connects through a second shunt coil 77b on contactor 70, to brush 74, located at such a radius from gear-shaft 18, as to contact properly with segment 76, normally just a little under a half-circle in extent, and positioned about as shown.

A third shunt-coil 77c on above contactor 70, is connected in the line 106 from the lower right-hand contact of double-pole, double-throw switch 78, to brush 79, in turn positioned to contact only with the short segment 80 on gear 73, positioned about as shown. Brush 81 bears on the ring 82, which feeds all the timing-segments just above mentioned, and is in turn connected through line 83, to wire 84, leading from contactor 70 to one pole of hand operated safety-switch 85, placed under pad-lock 86, inside cover of box 87. The live side of this switch 85 leads to insulated third-rail collector or shoe 8. Double-throw switch 78 is so arranged as to be thrown by the arm 88, operated either by the roller 89, or by a handle on same axis therewith, as desired, and built to stop in any one of the three notch positions shown, marked Fd for "forward", Rv for "reverse", and "off" respectively. This constitutes the travel limit-switch of the ingot-buggy, and at mill-end of tracks 3 or 29 will be functioned by a properly located side cam 90 which throws roll 89 to its upper level, while at furnace-end of track an inverted similar cam 91 will cause the downward throw of switch.

It will be noted that these cams will permit a slight or even considerable over-running of the ingot-buggy without injury to the parts operated, although co-ordinated means will be used to assure that such over-running will not occur.

Thus in series with the heavy main shunt field coil 92, of the main travel motor 5, of the 4:1 variable speed D. C. type, I have placed the speed control rheostat 93, whose operating arm 94 is normally held in the F or "fast" position by the heavy spiral spring 111, but which may be temporarily depressed to the lower or S "slow" position by a properly positioned side cam 95, a reversed duplicate of which is positioned near the other end of track, also, so as to contact with and push down roll 96, and thus slow down the carriage as the terminal limits of travel are approached, and well before switch 78 has to function.

To make doubly sure that the normal fairly high speed of travel of the ingot-car or buggy will be sufficiently reduced as it approaches the end positions, I have provided a double-wheel system as indicated in Figure 2, and arranged so that for the last ten feet or so of travel, the car will run on the auxiliary tracks 3a contacting with the much smaller diameter wheels 2a, and therefore again slowing down the speed. In case this

is not sufficient, or if preferred as an alternative means of slowing down, I have provided the underneath brake-pad 10, which may be made to readily function with a stationary spring-pressed brake-shoe of cast-iron properly positioned between the tracks as required, and arranged preferably so as to make pressure contact only as the carriage 1 is approaching the end of its travel, but not as the latter is accelerating in the opposite direction. This will be shown in a succeeding figure, along with adjusting means therefor.

The remaining terminal of contactor 70 connects directly to one brush lead of ingot-lift motor 20, the remaining brush connecting thru series field coil 97 to ground, or other return lead. Points 98, 99, and 100 indicate approximately the three normal stop positions of offset crank-shaft 18, as it moves through one revolution total in direction of the arrow. Shunt coils 101 and 102 function the double-pole, double-throw contactor 103 in such wise as to reverse the armature connections 104 and 105 of main travel motor 5, in well known manner, the contactor travel being down for "forward" and up for "reverse" motion of carriage, as indicated by the Fd and Rv markings. Coil 101 connects through lead 106 to timing brush 79, and at opposite end to upper right-hand terminal of switch 78, the right-hand middle terminal of which connects to ground, or common return line. The left middle terminal of this switch connects direct to trolley-arm 65 at its swivel-point, while lower left-hand terminal of 78 runs via wire 107 through the "forward" shunt coil 102, of contactor 103 to connect with line 108 leading to timing brush 71.

A tap from line 107 connects to lower "retaining-contact" 109 on contactor 103, and thence to ground, or return line. Lower-right and upper-right terminals of 103 go also to ground, while both left hand contacts go through the light series-coil 110 (if any), of motor 5, through magnetic-brake coil 6 to top terminal of safety switch 85, with branch taken off to one end of main variable shunt-coil 92 of this same motor, thence to the speed-varying rheostat 93, and through it to ground.

This completes my preferred form of connections, although substitute wiring might easily be devised to accomplish the same ends.

It is believed that the general mode of operation will be self evident, but in order to comply with requirements of the rules, I will carry the ingot-car through one complete cycle of operation, assuming the timing-brushes on crank-shaft 18 to be positioned as shown, switch 85 closed, but carriage 1 moved out to right-hand or furnace-end of track 3, and contacting only with trolley-wire 64, while cam 91 will have thrown switch 78 down by operating its arm 83 through roll 89.

Now, an ingot of circular type having been placed on the support 11, just over the ingot-lifting arm 15, and it being assumed that mill roll 27 has been already withdrawn fully so as to close the limit-contact 66, then as soon as the operator in pulpit near furnace-end of track closes the "starting push-button" contact 68, he closes a shunt-coil circuit leading from third-rail 1, through sliding-shoe 8, switch 85, wires 70 84 and 83 to timing-brush 81, ring 82, segment 72, brush 71, line 108, coil 102 of contactor 103, thence through wire 107 to lower-left terminal of switch 78, thru latter to trolley-arm 65, which being depressed by trolley-wire 64 is open at 75

auxiliary contact 69, leaving circuit to be completed through push-button 68, line 112, through mill-roll limit switch 66 to ground, or return line.

Coil 102 now energizing, contactor 103 is thrown down to "forward" running position, closing the "retaining" contacts 109 from line 107 direct to ground, and permitting current flow from switch 85 through series coil 6 of brake and 110 of motor 5, to lower throw of main reversing-contactor contacts 103 into and out of armature through 104 and 105 and to ground, it being noted that the main shut coil 92 of this motor has been alive from the time switch 85 was closed. This motor therefore starts up in the "forward" direction, whereupon the trolley-arm 65 leaves trolley-wire 64, closing auxiliary contact 69 to ground, as an added precaution to prevent any chattering at contacts 109 from stopping the forward travel. Now shunt-field rheostat arm 94 and roll 96 leave the furnace-end cam 95, and spring 111 pulls arm 94 up to the F or "fast" position, while the small wheels 2a of Figure 2 leave their stub-track sections 3a, as wheels 2 contact with the regular track 3, again accelerating the ingot-buggy, and it now proceeds on to the mill-end of track.

As it nears the mill, side-cam 95 depresses rheostat-arm 94 to the "slow" or S position, the wheels 2 leave the track 3, smaller wheels 2a engage with track 3a, and if desired the cast-iron brake shoe may be set to wipe the brake-pad 16 under pressure, all together acting to bring the carriage down to a very slow speed as it enters in under the mill 31 and the over-hung entering live-roll table 30.

As carriage now reaches the travel-limit cam 90 located at one side of the track and toward rear end of carriage 1, said cam throws switch 78 to its upper throw position, thereby opening the circuit of lower or "forward" coil of contactor 103, and allowing flat spring 113 on latter to return its moving element to neutral position, de-energizing motor 5, and its series brake-coil 6, throwing on this brake 6 and suddenly bringing the carriage 1 to a halt, in precision position immediately under the mill.

As the timing-brush 79 is not now connected to a segment on crank-shaft 18 or gear 73, the upper shunt-coil 101 of contactor 103 can not yet become energized, but mill-roll 27 being in "withdrawn" position, its limit-contact 66 will be still closed, so that a circuit can be traced from the live upper terminal of switch 85, through wires 84 and 83, to brush 81, ring 82, segment 72, brush 71, line 108, through upper shunt-coil 77a of ingot-lift motor contactor 70, trolley-arm 62, trolley-wire 63, line 112, mill-roll limit contact 66, to ground, or return line.

This leads to the energization of contactor 70, closing circuit from switch 85, through line 84, the contactor terminals, ingot-lift motor 20, series-coil 91 to ground, or return line, so that this motor now starts up, lifting the ring-ingot into precision alignment with the lower mill-roll position, at which point timing-brush 71 passes from segment 72, opening up contactor 70, and stopping motor 20.

Nothing further now happens, until mill-roll 27 has been retracted fully to its normal running position within the mill, when the limit-contact 67 is forced to close, whereupon a circuit can be traced from top of switch 85, through wires 84 and 83, to brush 81, ring 82, segment 76, brush 74, through middle shunt-coil 77b of contactor 70, to trolley-arm 63, trolley-wire 61,

through line 114 to and through limit-contact 67, to ground, again starting up the ingot-lift motor 20, which now runs until brush 74 leaves its segment 76, and once more stops this motor, leaving the arm 15 almost in its "down" position, and bringing brush 79 into contact with the very short segment 80.

Switch 78 having been thrown up at the time carriage 1 was brought to a halt, no circuit can be now traced through any coil of contactor 10, but one can be laid out from the now live brush 79, through lead 106 to the upper or "reverse" shunt-coil 101, of contactor 103, and on through the upper-right terminal of switch 78, down to its centre point and ground.

Contactor 103 therefore closes upward, or in "reverse" throw, and motor 5 again starts up slowly, but with its armature leads reversed, so that carriage 1 backs out away from the mill, the other speeding up factors taking place as explained before, and in proper sequence, so that the ingot-car speedily runs out to the furnace-end of track, often a very considerable distance away from the mill proper, and as before is brought to a gradual and accurate stop there, about as has been described in detail for the "forward" direction of its travel.

In case a flat-ingot 28 is to be delivered instead of a ring, the track switches are set manually to run the ingot-buggy in upon track 29 and directly up in line with the mill live-roll table 30, with the ingot-car roller table 25 close thereto and at the same level therewith, while the only trolley-arm now contacting will be the top one, 54, which connects herewith trolley-wire 58, appropriately positioned, and which places my live-roll table motor 51 directly in parallel with the driving motor 75, of the mill live-roll table, so that operator of latter can likewise function the live-roll table of my carriage, as required to deliver the new slab.

In this case, the mill roll 27 does not have to be removed, so that carriage 1 can be returned immediately to furnace-end as soon as slab has left its table 25.

An easy way to accomplish this is to add here two small trolley-wires similar to 68 and 61 previously mentioned, and set to contact with trolleys 62 and 63, just as before, but with both of these two trolley-wire sections connected together and then through a "starting push-button" at mill operator's pulpit, to ground.

On delivery of a new slab to the mill live-roll table 30, he presses this button for the few seconds required, causing ingot-lift motor 20 to idle through its usual stages, as before outlined, and in sequence finally starting the ingot-car back toward furnace-end of track, as already explained in detail.

If, at any time, switch 78 is thrown by hand to its centre, or "off" position, the car will be held idle, until this is again thrown in proper direction.

Or safety-switch 85 can be locked "open" if preferred. It is understood that all the separate slowing-down means cited need not be utilized on any one ingot-car, necessarily, but have been described so as to fairly well cover the subject, and it is probable that further extended study may lead to a material simplification of the wiring diagram, but still without departing from the spirit and scope of my invention.

With moderate and evident changes, my ingot-car might be adapted to alternating current motor, or even to steam or other type of engine

drive, and my claims are intended to cover such evident modifications.

Referring now to Figure 6, which is a transverse cross section of main track 3, and upper stub-track 3a, on one side of rear end of ingot-car and at mill end of track, and showing larger wheel 2, and smaller wheel 2a in rear elevation, I have indicated how the entrance of smaller wheel upon its track causes the larger to clear track 3, thus leading to a prompt reduction in speed of travel of the car.

This is easy for one axle, but in order to readily accomplish it for two sets of wheels in tandem, the driving gear on the "front" wheel axle is given about one or two teeth more than the gear required for "rear" axle, and the two respective wheels made in slightly larger and smaller diameters respectively, so that the "front" wheel will run in clear to end of track 3 and not contact with the upper track 3a until then, or until the same instant that "rear" wheel rides up on the short track 3a. This is brought out better in the side-view shown in elevation in Figure 7, where the diametral differences have been exaggerated in order to make the action clear. Here 115 indicates the "front" large wheel, 116 the small wheel there, while the "rear" large wheel is indicated at 2, and the small wheel here at 2a. But having the "rear" large wheel 2 smaller than the "front" wheel 115, does not work out well at the other end of track, where the furnaces are located.

So advantage is taken here of the heavy flange 117, on the "rear" wheel 2, to lift the carriage slightly, for the few first feet of length of travel onto the terminal track section 118, or until the trailing axle reaches the latter.

Thus the lower main track 119 is here made for a few feet of the grooved type, as shown in cross section in Figure 8, and the flange 117 of "rear" large wheel 2 is purposely turned to such a diameter as to contact therewith and raise this wheel well off of the upper track 118, until the grooved track 119 terminates, at which time the "rear" small wheel 2a drops slightly into bearing on upper track 118, at the same instant that "front" small wheel 116 of ingot-car first strikes the end of track 118. The flange 120 of "front" large wheel 115 is purposely turned to too small a diameter to contact at all with the groove in rail 119.

By the means cited both smaller wheels contact with the upper stub-track at the same instant, and at either end of the run between furnaces and mill.

In Figure 9, taken in side elevation, the track and wheel conditions at the furnace end of line, where the grooved rail is utilized, are brought out plainly.

In both Figures 7 and 9 it will be observed that the leading wheels to enter upon the upper stub-track section in the direction indicated by the arrows, do not contact at all with the upper track until the trailing wheels of the carriage contact therewith, at the same instant substantially.

It will be self-evident that a change-gear operated by a side cam such as 90 or 95, might be used to replace the auxiliary upper track and small wheel system cited. I have shown the special trackage system as my preferred arrangement, however, because of its relative sturdiness and lack of parts liable to cause maintenance difficulties, or expense, under oft-repeated functioning and severe service.

Similarly, it will be obvious to anyone skilled

in the art, that a purely manually operated carriage might be substituted for my preferred fully automatic type of machine, without departing from the spirit of my invention, and indeed I have provided for such hand operation at switch 88, if so preferred, a suitable rear-end step, or a seat, being then added for the operator, of course, as far away from the white-hot ingots as possible. The variable-speed rheostat arm 94, may have an operating handle also, placed in line with the roll 96, if so desired, and the whole mounted so as to be well within the reach of an operator on the car.

Further referring to Figure 9, I have shown at 121 a cast-iron brake-shoe suitable for contacting under pressure with the brake-pad 10 of carriage 1, as previously mentioned. Mounting links for said shoe are shown at 122, attached to convenient base 123, and held against the limit-stop 124, by means of the spring 125, in such wise that full contact pressure will be developed between 10 and 121 for the slowing down direction of travel of the car 1, but practically no retardation introduced during the acceleration in reverse direction, as carriage leaves the terminal position.

Means for adjusting the decelerating brake pressure exerted upon the pad 10, is indicated by the adjusting bolt 126, provided with nut 127, and lock-washer 128.

Instead of the electrical interlock contacts which I have utilized to determine that the mill was ready to receive a ring-ingot, before it was possible to start my ingot-buggy in the direction of the mill, it will be self-evident that any number of mechanical, or pneumatic interlocks might be devised for this purpose, but in general I prefer those of the electrical type, as being more certain of operation.

Certain very definite operative advantages accrue from the use of my ingot-carriage, in that it is capable of delivering either ring or straight ingots, or flat slabs, to the mill directly, at high speeds, low cost, and with the rings under slow rotation so that they will not cool down in spots, at the points of support.

Still further advantages accrue from the fact that my invention is capable of delivering ring-ingots with precision, and in rapid succession, right up into place in a continuous belt mill, such as that covered by my co-pending application.

Further important advantages accrue from the use of the rapid accelerating and decelerating automatic means provided, and the definite travel limit stops supplied.

While I have described a preferred embodiment of my present invention, it will be understood that changes in the construction or arrangement may be made without departing from the spirit of my invention, or the scope of my broader claims.

I claim:

1. In a circular-ingot transporting car, the combination comprising a power-driven carriage, energy-supply means therefor, accelerating and decelerating means operative at start and end of each run respectively, carriage reversing means, circular-ingot supporting means, an automatic travel limit-stop, and interlock means co-ordinating the start of carriage with the preparedness of mill to receive a new ingot.

2. In a circular-ingot transporting system, the combination of an ingot rolling mill, a substantially automatic power-driven ingot-carriage, energy-supply means therefor, multi-step automatic accelerating means at start, and multi-step de-

- celerating means operative at end of each run, automatic limit-stop means operative after deceleration, interlocked automatic ingot-delivery means into mill, and automatic reversal-of-travel 5 means operative after ingot delivery.
3. In an ingot transporting system, the combination comprising a live-roll type of support for flat-slabs, a separate live-roll support for circular ingots, a substantially automatic power-driven 10 carriage mounting both of said supports, and automatic interlock means delaying the start of carriage until mill roll system is prepared to receive the transported metal material.
4. A hot-ingot transport system comprising a substantially automatic ingot-car, energy-supply 15 means therefor, automatic decelerating, stopping and reversing means therefor, ingot-delivery means operative at mill-end of the travel, and an automatic interlock co-ordinating the approach 20 of car with the preparedness of mill to receive the transported material.
5. A hot-ingot transport system comprising a power-operable transport car, energy-supply means therefor, power-driven roller supports carrying said ingot, interlock timed and power-operable ingot delivery means, and a co-ordinating interlock operative to start said delivery means when mill is ready to receive the material.
6. An ingot transport system comprising a power-operable transport car, a source of energy-supply therefor, an interlock controlled starting means, an operation-sequence determining means, and an ingot delivery means controlled by this last mentioned means.
- 35 7. An ingot-transporting apparatus comprising an interlock operated starting device, automatic speed accelerating means of two distinct co-ordinated types, an automatic ingot-transport carriage accelerated thereby, speed decelerating means operative on said carriage thereafter, a subsequently operative travel limit stop, and properly timed ingot-delivery means operative at the stop position.
8. An ingot transporting apparatus comprising a manually controlled starting device, a power-operable metal-transport car controlled thereby, successively operable accelerating and decelerating mechanisms determining the point-to-point speeds of said car, a travel-limit stop precisely determining the ingot delivery position of said car, and an operation-sequence determining mechanism co-ordinating the successive movements of car and the period of ingot delivery at end of the travel thereof.
- 45 9. An ingot transporting apparatus comprising a power-propellable ingot-car, a source of power supply therefor, automatic accelerating and decelerating means, automatic stop and travel reversing means, ingot delivery means, a manually controlled initial starting means, and an operation-sequence timing device determining the succession of motions in both directions of car travel and the delivery of an ingot at proper point of the said travel.
10. An ingot transporting car comprising a power-propelled carriage, a source of power supply therefor, a manually controlled starting device for said carriage, a plurality of safety interlocks, and a timing device operative under the 60 control thereof, and together therewith determining the safe sequence of successive travel and ingot-delivery operations and the return to initial starting position of said car.
- 70 11. An ingot transporting car comprising a power-propelled traveling carriage, ingot carrying 75 means, travel-limit determining means, ingot delivery means, car reversing and returning means, a timing means determining the successive operations, and a cam operable device stopping said car near original starting point.
12. An ingot delivery car comprising a power-propelled traveling carriage, ingot carrying and final delivery means, and an operation-sequence timer coordinating the forward travel, stoppage, ingot delivery, return and final cam operated 10 halting of the said carriage at proper return position.
13. An ingot transport car comprising interlock controlled starting devices, co-ordinated with a manual starting means, and substantially automatic accelerating, slowing-down, precision stopping, ingot delivery, reverse starting, and final travel terminating means, co-ordinated in proper 15 definite sequence by a timer.
14. In an ingot-transport system, the combination comprising a power-propelled carriage, interlock-controlled manual starting means therefor, limit-stop controlled ingot-positioning means at mill, automatic ingot-delivery means, and a travel reversing means and return limit-stop, all 20 properly co-ordinated by an operation-sequence determining timer.
15. An ingot transport system comprising a power-propelled ingot-car, manually controlled starting means therefor, a circular-ingot support 30 mounted on said ingot-car, a travel limit-stop means determining final car position at mill-end of run, subsequently operative ingot-delivery means operative at mill-end of travel and under safety interlock control, and car reversing means 35 controllable by outside signal determined by longitudinal return of mill-roll to rolling position.
16. An ingot transport mechanism comprising a power-propelled ingot-car, a properly timable initial starting means therefor, substantially automatic stopping, ingot-delivery, and car-reversing means, an automatic operation-sequence timer properly co-ordinating the above, and an automatic final stopping means functional at 40 point close to initial starting position.
17. An ingot transporting means, comprising a power propellable multi-speed transport carriage, a live-roll flat-ingot receiving and delivery table operatively mounted on top of said carriage, a circular-ingot supporting arm mounted on one end 45 of said carriage and entirely separate from said live-roll table, and separate manual controls operatively connected to included power means to function said live-roll table, and to raise said supporting arm, as required, for their selective operation.
18. A hollow-circular-ingot transporting means, comprising a power propellable transport carriage, a combined circular-ingot supporting and power-rotating means providing slow-rotation of 60 said ingot about its longitudinal generating axis, to obviate localized cooling at the support positions, a precision limit-stop operative at mill position of said carriage to longitudinally align said circular-ingot with one roll axis of said mill, and included means operative to vertically align said ingot with the axis of said roll, as required for threading thereover.
19. An ingot transporting means, comprising a power propellable traveling carriage, a flat-ingot live-roll system mounted on said carriage, a separate circular-ingot carrying means provided with included means operative to slowly rotate said circular-ingot during transport, a track posi- 70

tioned on input side of a rolling-mill and providing proper alignment of said carriage horizontally for delivery of ingot from said live-roll system to the usual entering live-rolls of mill, and a separate track positioned on entering side of said rolling mill and providing proper alignment of a circular hollow ingot on said carrying means with the axis of one roll of mill, when required.

20. An ingot transport means, comprising a power propellable traveling carriage, a flat-ingot live-roll system mounted upon said carriage, connecting means operative to control the motion of said system manually, a separate ring-ingot carrying-means mounted at a lower level on same carriage than said live-roll system, and included means providing for accurate alignment of a ring-ingot removably mounted upon said carrying means, with axis of one roll of a rolling-mill into

which said ring-ingot is enterable by threading a previously removed roll therethrough.

21. An ingot transport means, comprising a power propellable multi-speed transport carriage, a live-roll flat-ingot delivery table operatively mounted on top of said carriage, a circular-ingot support means mounted on one end of said carriage and entirely below the line of said live-roll table, and connected control means operative to deliver flat-ingots in line with entering pass of a rolling mill from said live-roll table, and circular hollow ingots in position for threading over one roll of said mill from said support means, said ingot transport means including separate tracks for the motion of said carriage during the delivery of said flat and said circular ingots, respectively.
